(57) **CLAIM**

The ornamental design for an air fryer, as shown and described.

DESCRIPTION

FIG. 1 is a front perspective view of an air fryer

FIG. 2 is a front view thereof;

FIG. 3 is a rear view thereof;

FIG. 4 is a top view thereof;

FIG. 5 is a bottom view thereof;

FIG. 6 is a left view thereof;

FIG. 7 is a right view thereof; and,

FIG. 8 is a rear perspective view thereof.

The air fryer, as shown in FIGS. 1-8, has a housing in a substantially trapezoidal prism shape with rounded corners. The broken lines shown in the figures show features of the air fryer that form no part of the claimed design.

1 Claim, 8 Drawing Sheets
